(57) **CLAIM**

The ornamental design for a computer display with transitional musculoskeletal structure image, as shown and described.

DESCRIPTION

FIG. 1 is a front view of a first image of a musculoskeletal structure displayed as a portion of an interface within an electronic medical record system for computer display;

FIG. 2 is a front view of a second image thereof;

FIG. 3 is a front view of a third image thereof;

FIG. 4 is a front view of a fourth image thereof;

FIG. 5 is a front view of a fifth image thereof; and,

FIG. 6 is a front view of a sixth image thereof.

The appearance of the moving image sequentially transitions between the images shown in FIG. 1–6. The process or period in which an image transitions to another forms no part of the claimed design.

The broken line showing of a portion of a computer display is included for the purpose of illustrating environmental structure and forms no part of the claimed design.

In a particular embodiment, FIG. 1, FIG. 2, FIG. 3, FIG. 4, FIG. 5, and FIG. 6 provide the aesthetics of motion and apparition when displayed in sequence. For example, as an interface within an electronic medical record system changes to display a musculoskeletal structure from anatomical structure, the interface can provide an aesthetic that includes motion and appearance of anatomical features. In the exemplary embodiment of FIGS. 1 to 6, the interface of the electronic medical record system can provide an aesthetic transition from an anatomical structure, such as a foot, to a musculoskeletal structure included in the foot.
